DROP TABLE APPARATUS FOR USE IN SERVICING TRUCKS AND WHEELS OF RAILWAY VEHICLES

Asa W. Skinner, Riverdale Village, Ill., assignor to Whiting Corporation, Harvey, Ill., a corporation of Illinois

Application October 31, 1947, Serial No. 783,415

8 Claims. (Cl. 104—32)

1

The present invention relates generally to what is known in the art as drop table apparatus. More particularly the invention relates to that type of drop table apparatus which serves as a medium or instrumentality for removing trucks or wheels of railway vehicles in connection with repair, servicing or replacement thereof and is adapted for use with a main railway track having an interruption therein and an elongated pit extending transversely of the main railway track at the interruption therein and having a longitudinal track along its bottom.

A standard or conventional drop table apparatus has heretofore consisted of a unitary elevator and transfer car which is mounted on the track on the pit bottom to travel therealong and embodies a vertically movable table, and a rail equipped top which is designed to be raised and lowered by the table, is adapted when the elevator and transfer car is disposed adjacent the main track and the table is raised to the proper extent to be brought into a working position wherein its rails bridge and complete the rails of the main track and are so disposed that the railway vehicle truck or wheels to be serviced may be propelled thereon preparatory to release from the vehicle and subsequent lowering, and has mechanism whereby it may be locked in its operative or working position. In practice it has been found that a standard or conventional drop table apparatus of the last mentioned character effectively and efficiently fulfills its intended purpose, but it is subject to certain objections.

In the first place such an apparatus is costly to construct because of the numerous parts and elements of which it is composed. Secondly, because it embodies the rail equipped top in addition to the vertically movable table forming a part of the elevator and transfer car its overall height is such that it necessitates the use of a comparatively deep and costly pit.

The primary object of the invention is to provide a drop table apparatus which is an improvement upon and eliminates the objections to a standard or conventional apparatus of the aforementioned character and is characterized by the fact that it not only embodies fewer parts and is hence less costly to manufacture, but also requires or necessitates the use of a much more shallow pit. In general the improved apparatus comprises (1) a rectangular table which extends transversely across the pit, is vertically movable and has at its corners wheels for engaging the rails of the pit track when the table is lowered, (2) a plurality of vertically extending struts

2

which are so mounted with respect to the table that they and the table are relatively shiftable upwards and downwards, and (3) reversible power operated mechanism which is carried by the table, operates to effect relative up and down shift of the struts and the table, is adapted when actuated in one direction while the lower ends of the struts are at rest adjacent the bottom of the pit to raise the table to the top of the pit, and is further adapted when reversely actuated first to lower the table with respect to the struts until it is supported by its wheels on the pit track and then to raise the struts relatively to the table in order to release the latter so that it is free to be propelled along the pit track.

Another object of the invention is to provide a drop table apparatus of the last mentioned character in which the struts are four in number, are located at the corners of the table and have at the lower ends thereof forked members for straddling the rails of the track along the pit bottom.

A further object of the invention is to provide a drop table apparatus of the type and character under consideration in which the four struts at the corners of the vertically movable table are in the form of screw shafts and the reversible power operated mechanism for effecting relative vertical movement of the struts and the table comprises nuts which are mounted on the screw shafts and are carried at the corners of the table so that they are freely rotatable while at the same time they are held against vertical displacement with respect to the table.

A still further object of the invention is to provide a drop table apparatus of the character under consideration in which the fork forming members on the lower ends of the screw shafts constituting the vertically extending struts are downwardly tapered and are adapted, when the shafts are lowered preparatory to raising or elevating the table, to fit within socket equipped elements on the sides of the pit rails and to contact with such elements in such manner as to align the table with respect to the main railway track and also to hold the screw shafts together with the table against lateral displacement.

The invention also contemplates as one of its objects the provision of a drop table apparatus which is generally of new and improved construction, effectively and efficiently fulfills its intended purpose, and may be operated or manipulated with facility.

Other objects of the invention and the various advantages and characteristics of the present

drop table apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a top plan view showing a drop table apparatus embodying the invention in operative relation with a main railway track with an interruption therein and an elongated track equipped pit extending transversely of the main railway track at the interruption therein;

Figure 2 is an end elevation of the apparatus showing the table after it has been lowered so that the wheels thereof rest on the rails of the pit track;

Figure 3 is an end elevation showing the apparatus after it has been propelled along the pit track to another position within the pit and the table has been raised to a point adjacent the top of the pit;

Figure 4 is an enlarged vertical transverse section taken on the line 4—4 of Figure 1 and showing in detail certain parts of the reversible power operated mechanism for effecting relative vertical shift of the struts and the table;

Figure 5 is an enlarged but fragmentary vertical transverse section taken on the line 5—5 of Figure 1 and showing in detail the motor driven mechanism for driving certain wheels of the table in order to effect propulsion of the apparatus along the pit track;

Figure 6 is an enlarged vertical transverse section taken on the line 6—6 of Figure 1 and showing in detail the manner of mounting of the rotatable nuts which are mounted on the corners of the table and constitute parts of the reversible power actuated mechanism for effecting relative vertical shift of the struts and the table;

Figure 7 is a vertical transverse section taken on the line 7—7 of Figure 6 and illustrating the construction and design of one of the fork forming members at the lower ends of the screw shafts constituting the struts of the apparatus; and

Figure 8 is a section similar to Figure 7 except that it shows the form forming member in its fully lowered position on the subjacent pit rail and in operative or interfitting relation with the socket equipped element that is associated therewith.

The drop table apparatus which is shown in the drawing constitutes the preferred form or embodiment of the invention. It is adapted for use in connection with a main railway track 10 on a floor 11 and with an interruption or cutout therein and an elongated pit 12 and serves as a medium for effecting removal and replacement of the truck or wheels of a railway vehicle on the track 10. As described more in detail hereinafter the apparatus is brought into use when it is desired to remove, service and then remount the railway vehicle truck or wheels, and is also used in connection with a so-called release track 13 on the floor 11. The track 10 is suitably anchored on the floor 11 and consists of a pair of laterally spaced, sectional rails 14. The pit is formed in the floor 11 at the aforementioned cutout or interruption in the track 10. It is rectangular in cross section and extends

transversely of the track 10 as shown in Figures 1, 2 and 3. Certain of the sections of the rails 14 constituting the track 10 lead to and terminate adjacent one side of the pit 12 and other sections of the rails 14 lead to and terminate adjacent the other side of the pit. The floor 11 and the pit 12 are generally formed of concrete. The release track 13 is located at one side of the track 10, as shown in Figures 2 and 3. It is of the same gauge as the main railway track 10 and consists of a pair of laterally spaced sectional rails 15 which lead to and terminate adjacent the top of, the pit 12. On the bottom of the pit 12 is a longitudinally extending track 16 and this consists of a pair of laterally spaced rails 17 of conventional design. The last mentioned rails are suitably anchored to the bottom of the pit and serve to support the drop table apparatus and to permit the latter to travel along the pit. As its principal components the apparatus comprises a rectangular table 18 and four struts in the form of screw shafts 19.

The table 18 of the apparatus extends transversely across the pit 12 and is adapted to be raised and lowered in the pit as hereinafter described. It is fabricated from structural steel and consists of a pair of laterally spaced, parallel, longitudinally extending I-beams 20, a pair of laterally spaced, parallel, longitudinally extending channel beams 21, pairs of transversely extending channel beams 22 at the ends of the I-beams 20 and a pair of transversely extending channel beams 23 at the central portions of said I-beams. The aforementioned beams are welded or otherwise fixedly secured together so that the table 18 as a whole is rigid. The I-beams 20 are arranged so that the webs thereof extend vertically and are spaced apart a distance corresponding to the lateral spacing of the rails 14 as well as the rails 15. They are disposed inwards of, and in parallel relation with, the channel beams 21 and are so positioned and are of such length that the ends thereof terminate slightly inwards of the rails 17 constituting the pit track 16. The channel beams 21 are arranged so that the webs thereof extend vertically and are so positioned and are of such length that the ends thereof project across the rails 17 and terminate adjacent the sides of the pit 12. The pairs of transversely extending channel beams 22 at the ends of the I-beams 20 are arranged so that the webs thereof extend vertically and consist of inner channel beams and outer channel beams in spaced relation with the inner channel beams. The inner channel beams 22 have the central or intermediate portions thereof connected to the ends of the I-beams 20 and their ends connected to the end portions of the longitudinally extending channel beams 21 at points inwards of the outer extremities of said end portions. The outer transversely extending channel beams 22 are arranged in parallel relation with the inner channel beams 22 and have the ends thereof fixedly secured to the outer extremities of the end portions of the longitudinally extending channel beams 21. The transversely extending channel beams 23 adjacent the central portions of the I-beams 20 are spaced laterally apart and are positioned in parallel relation. They are arranged so that the webs thereof extend vertically and underlie and extend across the central portions of the beams 20 and 21. The upper flanges of the channel beams 23 are fixedly

secured to the lower flanges of the beams 20 and 21. The upper flanges of the I-beams 20 have fixedly mounted thereon a pair of laterally extending rail sections 24. These extend throughout the length of the I-beams 20 and are adapted when the table 18 is raised to the top of the pit while in alignment with the main railway track 10, to register with and bridge the rails 14 constituting the track 10. They are also adapted when the apparatus is positioned as shown in Figure 3 and the table thereof, is raised so that it is in alignment with the release track 13, to register with and bridge the rails 15 constituting the track 13. The table 18 is provided with four flanged wheels 25 in order that it may be propelled along the pit track 16 when it is lowered to the bottom of the pit 12. The wheels 25 are located adjacent the corners of the table and are disposed between the inner and outer transversely extending channel beams 22. They are mounted on stub shafts and these are journaled in bearings on the channel beams 22. The stub axles for two opposed or aligned wheels are connected by a horizontally extending shaft 26. The latter extends longitudinally of the table and is located beneath and adjacent one of the horizontally extending I-beams 20. A reversible electric motor 27 and speed reducing gearing 28 constitute reversible power operated mechanism for effecting propulsion of the apparatus in either direction along the pit track 16 when the table 18 is lowered so that the wheels 25 thereof rest on the rails 17. The electric motor 27 is supported adjacent the central portions of the I-beams 20 by way of a pair of horizontal, laterally spaced, transversely extending channel beams 29. The latter are located outwards of one of the channel beams 23 as shown in Figure 1, underlie the I-beams 20 and have the ends thereof suitably fixedly secured to the bottom flanges of said I-beams. The reversible electric motor 27 is so positioned that the armature shaft thereof extends lengthwise of the table 18. The speed reducing gearing 28 between the motor 27 and the shaft 26 consists of a housed gear type speed reducing unit 30, a chain and sprocket connection 31, a shaft 32 and a chain and sprocket connection 33, (see Figure 5). The gear type speed reducing unit 30 is mounted on the central portions of the channel beams 29 and has the casing of the electric motor 27 fixed to its housing. One end of the armature shaft of the motor 27 extends into the housing of the unit 30 and has one of the gears of the unit fixed to it. The chain and sprocket connection 31 extends between the driven gear of the unit 30 and one end of the shaft 32 and serves to drive the shaft 32 from the unit 30 in connection with drive of the electric motor 27. The shaft 32 extends lengthwise of the table 18 and is journaled in a pair of bearings 34, one of which is mounted on one of the channel beams 29 and the other of which is mounted on one of the channel beams 23. The chain and sprocket connection 33 extends between the other end of the shaft 32 and the central portion of the shaft 26 and serves to drive the last mentioned shaft in connection with drive of the first mentioned shaft. When the table 18 is lowered so that it is supported by the flanged wheels 25 on the rails 17 of the pit track 16 drive of the reversible electric motor 27 in one direction operates to effect propulsion of the drop table apparatus in one direction along the pit track. Reverse drive of the electric

motor 27 results in propulsion of the apparatus in the opposite direction along the pit track. The screw shafts 19 extend vertically and are located at the corners of the table 18. They directly overlie the rails 17 constituting the pit track 16 and are disposed outwards of the flanged wheels 25 and between the outer ends of the pairs of transversely extending channel beams 22. As hereinafter described the screw shafts 19 and the table 18 are movable or shiftable upwards and downwards relative to one another. The lower ends of the screw shafts are provided with fixed fork forming members 35 (see Figures 7 and 8). The latter are arranged in straddled relation with the heads of the pit rails 17 and coact therewith to prevent turning or rotating of the screw shafts in either direction. Each of the fork forming members consists of a pair of vertically extending laterally spaced plates 36. The upper ends of such plates fit against flats on the lower ends of the screw shafts 19 and are fixedly secured to the screw shafts by horizontally extending bolts 37, the shanks of which extend through aligned holes in the upper ends of the plates 36 and the lower ends of the screw shafts. The lower ends of the plates 36 are downwardly tapered and are adapted, when the screw shafts are lowered preparatory to raising or elevating the table to the top of the pit 12, to fit within either socket equipped elements 38 or socket equipped elements 39 on said pit rails 15. The elements 38 are disposed beneath and slightly outwards of the rails 14 of the main railway track 10. They are in the form of pairs of metallic blocks and these are riveted to opposite sides of the webs of the pit rails 17 and have on the central portions thereof upwardly and outwardly extending lugs 40 which define outwards of the heads of the pit rails upwardly flared sockets 41. The upward flare of the sockets 41 corresponds to the downward taper of the lower ends of the plates 36 constituting the fork forming members 35. The socket equipped elements 38 are so positioned on the rails of the pit track that when the screw shafts 19 are disposed thereabove in connection with proper positioning of the drop table apparatus and are then lowered preparatory to raising of the table 18, the downwardly tapered lower ends of the plates 36 enter the sockets 41 as shown in Figure 8 and coact therewith automatically to position the apparatus in such manner that the rail sections 24 are in vertical alignment with the rails 14 of the main railway track 10. The coaction between the lower ends of the plates 36 and the lugs 40 that define the upwardly flared sockets 41 is, in effect, a cam action. When the fork forming members 35 are positioned as shown in Figure 8 the lower ends of the screw shafts 19 rest on the heads of the pit rails 17 and the lower ends of the plates so interfit with the socket forming lugs 40 that the screw shafts together with the table 18 are held against lateral displacement. The fork forming members 35 and socket equipped elements 38 constitute aligning devices whereby when the apparatus is propelled substantially into registry with the cutout or interruption in the main railway track 10 and the screw shafts 19 are lowered the apparatus as a whole is cammed into true centered or registering relation with the main railway track rails 14. The socket equipped elements 39 are constructed in the same manner as, and function like, the elements 38. They are located in the pit beneath and slightly outwards of the rails 15 of the re-

lease track 13 and consist of pairs of blocks 42. The latter are arranged in straddled relation with, and are welded to, the webs of the pit rails 17 and have outwardly extending, upwardly divergent lugs 43 which define upwardly flared sockets 44 for receiving the lower downwardly tapered ends of the plates 36 constituting the fork forming members 35 on the lower ends of the screw shaft 19. When the drop table apparatus is propelled into registry with the rails 15 and the screw shafts are lowered so that the lower ends rest on the heads of the pit rails 17 the lower ends of the plates 36 slide into the upwardly flared sockets 44 and coact with the lugs 43 properly to center the apparatus with respect to the release track rails and also to hold the apparatus against lateral displacement.

The upper ends of the screw shafts 19 extend through sectional gear boxes 45 at the corners of the table 18 and have nuts 46 mounted thereon. The gear boxes are four in number and are suitably fixedly secured within cutouts 47 in the lower end corners of the transversely extending channel beams 22. They are preferably in the form of metallic castings and consist of inverted cup-shaped upper sections 48 and plate like lower sections 49 (see Figure 6). The central portions of the upper sections 48 of the gear boxes are provided with integral, depending, open ended sleeves 50 and the central portions of the lower sections 49 are provided with integral, upwardly extending, open ended sleeves 51. The latter are in coaxial relation with the depending sleeves 50. The outer margins of the lower sections 49 of the gear boxes are bolted or otherwise removably secured to the lower ends of the side walls of the upper sections 48. The screw shafts 19 extend through the sleeves 50 and 51. The nuts 46 are disposed in the central portions of the interiors of the gear boxes and are interposed between the adjacent ends of the sleeves 50 and 51. They are capable of rotating relatively to the gear boxes but are held against axial displacement relatively to said gear boxes. Roller type thrust bearings 52 are interposed between the upper ends of the nuts and the lower ends of the sleeves 50. When the nuts 46 are conjointly rotated in one direction while the table 18 is supported on the pit track 16 by the wheels 25 the screw shafts 19 are fed downwards until the lower ends thereof rest on the rails of the pit track. Thereafter the table is caused to be raised or shifted upwards towards the top of the pit. When the nuts 46 are conjointly rotated in the opposite direction the table 18 is caused to be lowered until the wheels 25 thereof rest on the rails of the pit track. Thereafter the screw shafts are caused to move upwards to a slight extent in order to cause the fork forming members 35 to be withdrawn from interfitting relation with the sockets of the socket equipped elements on the webs of the rails 17 and thus free the apparatus so that it is capable of being propelled in either direction along the pit track 16.

In addition to the parts heretofore specifically described the drop table apparatus comprises reversible power actuated mechanism 53 for conjointly turning the nuts 46 in one direction or the other. Such mechanism consists of a reversible electric motor 54 and gearing between the motor and the nuts. The motor 54 is located at the central portion of the table 18 and is suitably secured to a cradle 55 which extends across, and is secured to, the central portions of the transversely extending channel beams 23. As best

shown in Figure 1, the motor 54 is positioned or arranged so that the armature shaft thereof extends transversely of the table. The gear between the motor 54 and the nuts 46 consist of a pair of sectional shafts 56, a pair of gear type speed reducing units 57, four sectional shafts 58, four worms 59 and four worm gears 60. The speed reducing units 57 are mounted on the ends of the transversely extending channel beams 23 and, as shown in Figure 1, are positioned equidistantly between the gear boxes 45. The shafts 56 are horizontal and extend transversely of the table 18. They are positioned at opposite ends of the reversible electric motor 54 and have the inner ends thereof connected by flexible or universal couplings to the ends of the armature shaft of said motor. The outer ends of the shafts 56 extend into the speed reducing units 57 and are connected to certain gears (not shown) in such units. The shafts 58 are horizontal and extend lengthwise of the table. They are disposed directly inwards of, and in parallel relation with, the longitudinally extending channel beams 21 of the table and extend between the speed reducing units 57 and the gear box 45. The inner ends of the shafts 58 are fixedly connected to certain of the driven gears of the speed reducing units and the outer ends of such shafts extend into the gear boxes 45 and have the worms 59 fixedly connected thereto. The worm gears 60 surround, and are fixedly secured to, the nuts 46 and mesh with the worms 59. The gearing between the reversible electric motor 54 and the nuts 46 is such that when the motor is driven in one direction it causes the nuts conjointly to rotate in one direction and when such electric motor is driven in reverse direction it operates or causes the nuts conjointly to rotate in the opposite direction.

When it is desired to utilize the drop pit apparatus to service a truck or a pair of wheels of a railway vehicle on the track 10 the apparatus is first propelled along the pit track until it is adjacent the cutout or interruption in the track 10. Propulsion of the apparatus is effected by driving the electric motor 27 in the proper direction. As soon as the apparatus is properly located or positioned the electric motor 54 is operated so that it, through the medium of the gearing including the shafts 56, the speed reducing units 57, the shafts 58, the worms 59 and the worm gears 60, operates so to rotate the nuts 46 as to cause the screw shafts 19 to move downwards. As the screw shafts move downwards the lower ends of the plates 36 constituting the fork forming members 35 enter the sockets 41 and coact with the lugs 40 of the elements 39 properly to effect centering or alignment of the apparatus. After the lower ends of the screw shafts 19 are brought to rest on the heads of the rails 17 of the pit track 16 continued operation of the electric motor 54 in the same direction effects raising of the table 18. Such motor is stopped when the table 18 reaches the top of the pit 12 and its rail sections 24 are in registry with and serve to bridge or form continuations of the rails 14 of the main railway track 10. After the table is properly positioned at the top of the pit the railway vehicle is propelled along the track 10 until the truck or the wheels to be serviced are disposed on the rail sections 24 on the table. Thereafter release of the truck or wheel is effected. After such operation the electric motor 54 is reversely driven so as to cause conjoint reverse rotation of the nuts 46. Such rotation on the part of the nuts first

causes the table 18 to be lowered until its wheels 25 rest on the pit rails 17 and then causes the screw shafts to be raised with respect to the table. As soon as the screw shafts are raised to a slight extent so that the fork forming members 35 are disengaged from the socket equipped elements 39 the apparatus is propelled along the pit track 16 until it is adjacent the release track 13. After such propulsion on the part of the apparatus the motor 54 is operated in such direction that it operates through the medium of the gearing between it and the nuts 46 first to lower the screw shafts 19 and then, after the screw shafts are brought to rest on the pit rails 17, to effect raising of the table. When the table is at the top of the pit 12 with its track section 24 in registry and bridging relation with the rails 15 of the release track the motor 54 is stopped. Thereafter the truck, for example, is propelled along the release track to the point where it is serviced or repaired. After repair the truck is propelled back onto the rail section 24 and the table 18, by proper actuation of the mechanism 53, is lowered until its wheels 25 rest on the rails of the pit track 16. As soon as the table is so lowered the apparatus is propelled back to its original position wherein it is adjacent the cutout or interruption in the main railway track 10. Thereafter mechanism 53 is actuated so as to raise the table 18 into its working position wherein its rail sections 24 bridge and serve to complete the rails 14 of the main railway track 10. At the conclusion of this operation the truck is connected to its railway vehicle and such vehicle is in condition to be propelled along the track 10.

The herein described drop table apparatus is highly efficient so far as operation is concerned and is characterized by the fact that it consists of but a comparatively small number of parts and hence may be produced at a low cost. By reason of the fact that the wheels 25 are mounted directly on the table 18 and the raising and lowering mechanism for the table includes screw shafts 19 the overall height of the apparatus is essentially small and as a result it is possible to make the pit 12 quite shallow so far as depth is concerned.

Whereas the apparatus has been described as having rail sections on the top 18 it is to be understood that the top, instead of having rail sections, may be used to raise and lower a separable rail section equipped top having locking means for locking it at the top of the pit. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. A drop table apparatus having associated therewith a main railway track with an interruption therein and an elongated pit extending transversely of the main track at said interruption and having a longitudinal track along its bottom, designed for use in removing and then replacing wheels on a railway vehicle on the main track, and comprising a table extending across the pit, adapted to be raised and lowered in the pit and when in its raised position while adjacent the main track to bridge the interruption and permit the wheels to be propelled thereover, and having mounted directly thereon wheels adapted when the table is in its lowered position

in the pit to rest on the pit track and permit the table to be propelled therealong, a plurality of vertically extending struts connected to the table so that they and said table are capable of relative raising and lowering movement, and reversible power operated mechanism mounted on the table, operative to effect relative raising and lowering movement of the struts and table, and so related to said struts that it is adapted when actuated in one direction after the lower ends of the struts are supported at the pit bottom and the table is in its raised position first to lower the table until the wheels thereof rest on the pit track and then to raise the struts relatively to the table and free the latter so that it is capable of being propelled along the pit track, and is further adapted when actuated in the opposite direction first to lower the struts until the lower ends thereof are supported at the bottom of the pit and then to raise the table.

2. A drop table apparatus having associated therewith a main railway track with an interruption therein and an elongated pit extending transversely of the main track at said interruption and having a longitudinal track along its bottom and in the form of a pair of laterally spaced rails, designed for use in removing and then replacing wheels on a railway vehicle on the main track, and comprising a unitary rectangular table extending across the pit, adapted to be raised and lowered in the pit and when in its raised position while adjacent the main track to bridge the interruption and permit the wheels to be propelled thereover, and having mounted directly thereon wheels adapted when the table is in its lowered position in the pit to rest on the rails of the pit track and permit the table to be propelled along the latter, four vertically extending struts positioned directly above the rails and connected to the corner portions of the table so that they and said table are capable of relative raising and lowering movement, and reversible power operated mechanism mounted on the table, operative to effect relative raising and lowering movement of the struts and table, and so related to the struts that it is adapted when actuated in one direction after the lower ends of the struts are at rest on the rails and the table is in its raised position first to lower the table until the wheels thereof rest on the pit track and then to raise the struts relatively to the table and free the latter so that it is capable of being propelled along the pit track, and is further adapted when actuated in the opposite direction first to lower the struts until the lower ends thereof rest on said rails and then to raise the table.

3. A drop table apparatus having associated therewith a main railway track with an interruption therein, and an elongated pit extending transversely of the main track at said interruption and having a longitudinal track along its bottom and in the form of a pair of laterally spaced rails, designed for use in removing and then replacing wheels on a railway vehicle on the main track, and comprising a unitary rectangular table extending across the pit, adapted to be raised and lowered in the pit and when in its raised position while adjacent the main track to bridge the interruption and permit the wheels to be propelled thereover, and having mounted on its corner portions four wheels adapted when the table is in its lowered position in the pit to rest on the rails of the pit track and permit the table to be propelled therealong, four vertically extending struts positioned directly above the rails

and outwards of the wheels on the table and connected to the table so that they and said table are capable of relative raising and lowering movement, and reversible power operated mechanism mounted on the table, operative to effect relative raising and lowering movement of the struts and table, and so related to the struts that it is adapted when actuated in one direction after the lower ends of the struts are at rest on the rails and the table is in its raised position first to lower the table until the wheels thereof rest on the pit track and then to raise the struts relatively to the table and free the latter so that it is capable of being propelled along the pit track, and is further adapted when actuated in the opposite direction first to lower the struts until the lower ends thereof are at rest on said rails and then to raise the table.

4. A drop table apparatus having associated therewith a main railway track with an interruption therein and an elongated pit extending transversely of the main track at said interruption and having a longitudinal track along its bottom and in the form of a pair of laterally spaced rails, designed for use in removing and then replacing wheels on a railway vehicle on the main track, and comprising a rectangular table extending across the pit, adapted to be raised and lowered in the pit and when in its raised position while adjacent the main track to bridge the interruption and permit the wheels to be propelled thereover, and having mounted directly thereon wheels adapted when the table is in its lowered position in the pit to rest on the rails of the pit track and permit the table to be propelled along the latter, four vertically extending struts positioned directly above the rails, provided at their lower ends with fork-like members for straddling said rails and connected to the corner portions of the table so that they and said table are capable of relative raising and lowering movement, and reversible power operated mechanism mounted on the table, operative to effect relative raising and lowering movement of the struts and table, and so related to the struts that it is adapted when actuated in one direction after the lower ends of the struts are at rest on the rails and the table is in its raised position first to lower the table until the wheels thereof rest on the pit track and then to raise the struts relatively to the table and free the latter so that it is capable of being propelled along the pit track, and is further adapted when actuated in the opposite direction first to lower the struts until the lower ends thereof rest on said rails and then to raise the table.

5. A drop table apparatus having associated therewith a main railway track with an interruption therein and an elongated pit extending transversely of the main track at said interruption and having a longitudinal track along its bottom and in the form of a pair of laterally spaced rails designed for use in removing and then replacing wheels on a railway vehicle on the main track, and comprising a unitary rectangular table extending across the pit, adapted to be raised and lowered in the pit and when in its raised position while adjacent the main track to bridge the interruption and permit the wheels to be propelled thereover, and having mounted directly thereon wheels adapted when the table is in its lowered position in the pit to rest on the rails of the pit track and permit the table to be propelled along the latter, four ver-

tically extending struts positioned directly above the rails, provided at their lower ends with fork-like members for straddling said rails, and connected to the corner portions of the table so that they and said table are capable of relative raising and lowering movement, reversible power operated mechanism mounted on the table, operative to effect relative raising and lowering movement of the struts and table, and so related to the struts that it is adapted when actuated in one direction after the lower ends of the struts are at rest on the rails and the table is in its raised position first to lower the table until the wheels thereof rest on the pit track and then to raise the struts relatively to the table and free the latter so that it is capable of being propelled along the pit track, and is further adapted when actuated in the opposite direction first to lower the struts until the lower ends thereof rest on said rails and then to raise the table, and block-like elements secured to the rails at points adjacent the railway tracks and having upwardly flared sockets adapted when the table is propelled along the pit track into a position under the interruption and the mechanism is initially actuated in said opposite direction for strut lowering purposes to receive the fork-like members and coat therewith in such manner as to hold the struts against lateral displacement.

6. A drop table apparatus having associated therewith a main railway track with an interruption therein and an elongated pit extending transversely of the main track at said interruption and having a longitudinal track along its bottom, designed for use in removing and then replacing wheels on a railway vehicle on the main track, and comprising a unitary table extending across the pit, adapted to be raised and lowered in the pit and when in its raised position while adjacent the main track to bridge the interruption and permit the wheels to be propelled thereover, and having mounted directly thereon wheels adapted when the table is in its lowered position in the pit to rest on the pit track and permit the table to be propelled thereon, a plurality of vertically extending struts in the form of screw shafts connected to the table so that they and said table are capable of relative raising and lowering movement, reversible power operated mechanism mounted on the table, operative to effect relative raising and lowering movement of the screw shafts and table, so related to the struts that it is adapted when actuated in one direction after the lower ends of the screw shafts are supported adjacent the pit bottom and the table is in its raised position first to lower the table until the wheels thereof rest on the pit track and then to raise the screw shafts relatively to the table and free the latter so that it is capable of being propelled along the pit track, and is further adapted when actuated in the opposite direction first to lower the screw shafts until the lower ends thereof are supported adjacent the bottom of the pit and then to raise the table, and consisting of a reversible electric motor, nuts rotatably mounted on the screw shafts and held on the table against axial displacement relatively thereto, and gearing extending between the motor and nuts and operative conjointly to rotate the nuts in one direction when the motor is driven in one direction and conjointly to rotate the nuts in the opposite direction when the motor

tor is reversely driven, and means associated with the struts for holding the latter against rotation relatively to the table.

7. A drop table apparatus having associated therewith a main railway track with an interruption therein and an elongated pit extending transversely of the main track at said interruption and having a longitudinal track along its bottom and in the form of a pair of laterally spaced rails, designed for use in removing and then replacing wheels on a railway vehicle on the main track, and comprising a unitary rectangular table extending across the pit, adapted to be raised and lowered in the pit and when in its raised position while adjacent the main track to bridge the interruption and permit the wheels to be propelled thereover, and having mounted directly thereon wheels adapted when the table is in its lowered position in the pit to rest on the rails of the pit track and permit the table to be propelled therealong, four vertically extending screw shafts positioned directly above the rails, connected to the corner portions of the table so that they and said table are capable of relative raising and lowering movement, reversible power operated mechanism mounted on the table, operative to effect relative raising and lowering movement of the screw shafts and table, so related to the struts that it is adapted when actuated in one direction after the lower ends of the screw shafts are at rest on the rails and the table is in its raised position first to lower the table until the wheels thereof rest on the pit track and then to raise the screw shafts relatively to the table and free the latter so that it is capable of being propelled along the pit track, and is further adapted when actuated in the opposite direction first to lower the screw shafts until the lower ends thereof are at rest on said rails and then to raise the table, and consisting of a reversible electric motor, nuts rotatably mounted on the screw shafts and held on the table against axial displacement relatively thereto, and gearing extending between the motor and nuts and operative conjointly to rotate the nuts in one direction when the motor is driven in one direction and conjointly to rotate the nuts in the opposite direction when the motor is reversely driven and

means associated with the struts for holding the latter against rotation relatively to the table.

8. A drop table apparatus having associated therewith a main railway track with an interruption therein, and an elongated pit extending transversely of the main track at the interruption and having a longitudinal track along its bottom, designed for use in removing and then replacing wheels on a railway vehicle on the main track, and comprising a unitary table extending across the pit, having rail sections on the top thereof, adapted to be raised and lowered in the pit and when in its raised position while adjacent the main track to have its rails bridge the interruption and permit the wheels to be propelled thereover, and having mounted directly thereon wheels adapted when the table is in its lowered position in the pit to rest on the pit track and permit the table to be propelled therealong, a plurality of vertically extending struts connected to the table so that they and said table are capable of relative raising and lowering movement, and reversible power operated mechanism mounted on the table, operative to effect relative raising and lowering movement of the struts and table, and so related to the struts that it is adapted when actuated in one direction after the lower ends of the struts are supported adjacent the pit bottom and the table is in its raised position first to lower the table until the wheels thereof rest on the pit track and then to raise the struts relatively to the table and free the latter so that it is capable of being propelled along the pit track, and is further adapted when actuated in the opposite direction first to lower the struts until the lower ends thereof are supported adjacent the bottom of the pit and then to raise the table.
